UNITED STATES PATENT OFFICE.

ARTHUR TREVOR DAWSON, OF WESTMINSTER, LONDON, AND JAMES HORNE, OF BARROW-IN-FURNESS, ENGLAND, ASSIGNEES, BY MESNE ASSIGNMENTS, TO VICKERS LIMITED, OF WESTMINSTER, ENGLAND.

AMMUNITION-LOADING APPARATUS FOR HEAVY GUNS.

1,071,606.

Specification of Letters Patent.

Patented Aug. 26, 1913.

Application filed December 4, 1909. Serial No. 531,356.

To all whom it may concern:

Be it known that we, ARTHUR TREVOR DAWSON and JAMES HORNE, both subjects of the King of Great Britain, residing, respectively, at 32 Victoria street, Westminster, in the county of London, England, and Naval Construction Works, Barrow-in-Furness, in the county of Lancaster, England, have invented certain new and useful 10 Improvements in or Relating to Ammunition-Loading Apparatus for Heavy Guns, of which the following is a specification.

This invention relates to ammunition loading apparatus for heavy guns of the 15 kind wherein the powder charges and projectiles are elevated to the loading position by cages which in their ascent lie in a more or less vertical position and are tilted about their transverse axes so as to come to rest 20 in a more or less horizontal position behind the gun breech.

The chief object of the present invention is to enable projectiles of increased length to be used without materially increasing the 25 usual distance that exists between the gun breech and the rammer when the gun is in the loading position. That is to say although the length of the projectiles is greater than the aforesaid distance, we are 30 yet enabled to bring them into a longitudinal position between the said gun breech and rammer. We can thus use projectiles of increased length without making the turntable of increased diameter which would be 35 objectionable on account of the additional weight that would be involved and the increased power required for actuating it.

Our invention can also be employed with the object of reducing the usual clearance 40 at the rear of the gun, in connection with projectiles of ordinary length, so that we can effect a reduction in the size of the turntable and obtain all the advantages that arise by such reduction.

45 According to our invention we transversely pivot the projectile tray to the cage which carries the powder charges in a hori-

zontal or approximately horizontal position and we provide means whereby, during the ascent of the cage, the said tray occupies 50 an inclined or oblique position relatively to the powder charges and upon the cage approaching the completion of its elevation and the nose of the projectile reaching a position adjacent to the gun breech, the said 55 tray is caused to assume a position to bring the projectile more or less parallel to the powder charges and in alinement with the axis of the gun with its base opposite the rammer. It will be obvious that while the 60 projectile tray is in its inclined position the linear horizontal distance between its nose and base is less than such distance when the projectile occupies its position co-axial with the gun breech and that as the breech is 65 open during the pivotal movement of the projectile tray into the position co-axial with the breech, the nose of the projectile is able to enter the breech to an extent that will compensate for the excess in the length 70 of the projectile over that of the distance between the breech and the rammer.

In order that our said invention may be clearly understood and readily carried into effect, we will describe the same more fully 75 with reference to the accompanying drawings, in which:

Figure 1 is a sectional elevation and Fig. 2 a sectional plan of a gun mounting provided with one form of our improved powder charge cage. Fig. 3 is a sectional elevation showing a modified form of our improved powder charge cage. Fig. 4 is a sectional elevation showing another modified form of our improved powder charge cage. Figs. 5 and 6 are respectively a side elevation and a cross-section of the powder charge cage drawn on a larger scale. Fig. 7 is a sectional elevation showing a still further modified form of our improved powder 85 charge cage.

Like letters of reference indicate similar parts in all the figures.

A is the gun, B the turntable and C the

powder charge cage, which in the drawings is represented by the loading cage that lifts the ammunition from the working chamber to the gun.

5 D' are the rails by which the cage is guided in its ascent and descent to and from the gun breech.

E is the working chamber wherein the loading cage receives the powder charges 10 and projectile from the central hoist F by any of the usual methods.

G is the rammer.

C' is the projectile tray which is hinged to the cage by a transverse pivot c so as to 15 permit of the said tray assuming its aforesaid inclined or oblique position during the ascent of the cage and of assuming a more or less horizontal position in alinement with the gun when the cage reaches its fully 20 raised position.

Any appropriate means may be employed for the purpose of causing the said pivoted projectile tray to move from its inclined to its horizontal position; in the drawings we 25 have shown the said tray provided with an arm c' which as the loading cage approaches the completion of its upward movement is acted upon by a suitably arranged cam piece h. When the gun is adapted to be loaded 30 at any angle of elevation this cam piece is situated on the loading arm A'x of the gun slide A² in the manner illustrated by way of example in Figs. 1 and 2. When the gun is adapted to be loaded in a predetermined position the said cam may be situated in a 35 fixed position as shown by way of example in Fig. 3, the said cam piece in this case forming part of a grooved guide rail h' in which the free end of the said arm c' travels 40 during the ascent and descent of the cage. In Figs. 1 and 2 a spring c² is provided for returning the projectile tray to its inclined position as the cage leaves the aforesaid cam piece h and descends. In Fig. 3 the said tray 45 is adapted to assume this position under the influence of the guide rail h' without the assistance of a spring.

In order to bring the said tray to a more or less horizontal position when the cage 50 reaches its lowered position for receiving the projectile, we provide a cam piece h² (Figs. 1, 2 and 3) for acting upon the said arm c' as the cage completes its descent, the said cam piece in Fig. 3 forming part of the guide rail h'.

The projectile tray may be arranged to assume its inclined position by tilting so that the rear part thereof moves either upward or downward about its pivotal connection with 60 the cage; in the latter case the projectile lies with its base lowermost and resting against a ledge c³ on the tray as in Figs. 1 and 3; in the former case the said projectile lies with

its nose lowermost and resting against a removable lip or stops c⁴ as in Figs. 4 to 7.

65

In the arrangements illustrated by Figs. 4 to 7 wherein the pivot c is situated near the forward end of the tray and the projectile is raised nose downward, a catch or similar contrivance is required for retaining the 70 tray in its inclined position during the upward movement of the cage, the said catch being adapted to be liberated as the cage completes its upward movement, so that the tray will then assume its position for bringing the projectile in alinement with the gun breech by the action of gravity. In the examples shown the said catch is in the form of a spring bolt h⁶ (Fig. 6) mounted on the cage and adapted to engage with a recess c⁵ 80 in the projectile tray when the latter is tilted into the inclined position and said recess comes opposite the bolt. As the cage reaches its upper position this bolt is disengaged from the recess in the projectile tray so as to 85 permit the latter to assume the horizontal position by means of a cam piece h⁸ acting upon a rocking arm h¹⁰ connected with the said bolt.

In order to retain the projectile in place 90 in the tray as the cage is ascending we provide the pivot about which the tray swings with a loose arm c⁶ carrying the aforesaid movable stop or lip c⁴ and this loose arm has an extension c⁸ engaging with a spring 95 c⁹. This spring normally tends to keep the said arm in a position with the stop or lip c⁴ in front of the nose of the projectile during the ascent of the cage. As the cage completes its upward journey the catch bolt h⁶ 100 is released by the cam piece h⁸, whereupon the projectile tray assumes its horizontal position, the arm c⁶ being prevented from participating in this movement of the projectile tray by bearing against the loading tray A'. Therefore when the projectile tray is in the 105 horizontal position, the stop or lip c⁴ lies in a position in which it will offer no impediment to the ramming of the projectile into the gun. In these arrangements also a 110 resilient stop or buffer h⁷ is provided for the tray to come against as it assumes its position in alinement with the gun breech by the action of gravity. We furthermore provide a bearing surface g against which the base 115 of the projectile bears while the tray is assuming its horizontal position at the gun breech, thus causing the said projectile to move inwardly along the tray and introduce its nose into the gun breech. This bearing surface g is not required when the projectile tray assumes an inclined position with its base downward (as in Figs. 1 to 3) because the action of the tray in assuming its horizontal position at the gun breech causes the 120 nose of the projectile to be introduced into

75

the breech. It will of course be understood that the breech will be fully opened and the loading tray A' will be turned into its operative position before the cage completes its ascent so as to leave the breech ready to receive the nose of the projectile. If found convenient the said tray may be allowed to remain in its inclined position when the cage reaches its lowered position in which case 10 the aforesaid cam piece h² would be unnecessary.

In the arrangement shown by Figs. 4 to 7 the projectile tray, when empty, does not become tilted or inclined during the descent 15 of the cage, the length of said tray being less than that of the projectile and less than the distance between the gun breech and the rammer. The said tray becomes tilted into its inclined position as the cage ascends by 20 the action of the cam h^x in the construction shown in Figs. 4 to 6 and by a spring controlled hinged flap or switch h³ in the construction shown in Fig. 7. In the former arrangement (Figs. 4 to 6) the said cam h^x 25 is formed with an inclined portion at its upper part and a double inclined portion at its lower part, a cam piece h⁹ being suitably arranged for acting upon the rocking arm h¹⁰ of the catch bolt h⁶ on the cage so as to 30 keep said catch bolt retracted during the time that the cage is passing the cam h^x in completing its descent. The upper inclined portion of the said cam h^x acts upon the arm c' of the projectile tray and temporarily 35 rarely tilts the said tray in order to bring the said arm c' into the double inclined portion at the lower part of the cam h^x the said tray resuming its horizontal position as the arm c' passes down the double inclined portion of the cam. After the tray has been 40 charged with the projectile and as the cage is caused to ascend, the double inclined portion of the cam acts upon the arm c' and causes the cage to be again tilted, the intervening portion of the cam h^x between the 45 inclined portions thereof holding the arm and therefore the tray in the tilted position until in the continued ascent of the cage, the rocking arm h¹⁰ has cleared the cam piece h⁹ 50 and permitted the catch bolt h⁶ to engage with the projectile tray in order to lock it in the tilted or inclined position. The said tray is thus retained in the inclined position until the cage approaches the completion 55 of its ascent and the cam piece h⁸ releases the catch bolt h⁶ as before explained. In the arrangement shown by Fig. 7, the free end of the arm c' travels along the outer side of the aforesaid hinged switch h³ as the cage 60 descends. The said switch occupies an inclined position and gives way as the cage descends thus permitting the tray to remain in its horizontal position. As the cage as-

cends the free end of the said arm c' travels along the inner side of the said inclined flap 65 or switch and causes the tray to tilt into its inclined position by reason of the flap or switch being held rigidly against a stop h⁴ by the action of its spring h⁵.

The term "horizontal" above used in 70 connection with the projectile tray is intended to include any approximately horizontal position the said tray may assume when it is tilted about its pivot to bring the projectile into alinement with the gun breech and 75 the rammer.

We do not desire to limit ourselves to the use of the aforesaid pivoted projectile tray with a cage for supplying the ammunition from the working chamber E to the gun 80 breech, as it is obvious that the said tray can with advantage be used with the cages commonly employed for raising the projectiles from the shell rooms to the working chamber. 85

What we claim and desire to secure by Letters Patent of the United States is:—

1. In gun loading apparatus, the combination with the powder charge cage, of a pivoted projectile tray, means whereby the 90 said tray occupies an inclined position during its ascent, and means for causing the said tray upon reaching the gun breech to assume a position in which the nose of the projectile enters the breech. 95

2. In gun loading apparatus, the combination with the powder charge cage, of a projectile tray transversely pivoted thereto, means whereby said tray occupies an inclined position during its ascent and means 100 for automatically causing said tray to assume a position in alinement with the gun upon reaching the gun breech.

3. In gun loading apparatus, the combination with the powder charge cage, of a 105 projectile tray pivoted thereto, means whereby said tray occupies an inclined position during its ascent, means for causing said tray to assume a position in alinement with the gun upon reaching the gun breech 110 with the nose of the projectile entering the breech.

4. In gun loading apparatus, the combination with the powder charge cage, of a 115 projectile tray transversely pivoted thereto, an arm on said tray, and means coöperating with said arm when the powder charge cage completes its upward movement to rock the tray about its pivotal connection with the powder charge cage and cause it to assume a 120 position in alinement with the gun.

5. In gun loading apparatus, the combination with the powder charge cage, of a projectile tray transversely pivoted thereto, an arm on said tray, and a cam piece with 125 which the said arm coöperates when the

loading tray completes its upward movement and cause it to assume a position in alignment with the gun.

6. In gun loading apparatus, the combination with the powder charge cage, of a projectile tray transversely pivoted thereto, an arm on said tray, a fixed cam piece with which the said arm coöperates when the loading tray completes its upward movement, 10 and a second fixed cam piece which acts upon said arm as the cage completes its descent.

7. In gun loading apparatus, the combination with the powder charge cage, of a 15 projectile tray transversely pivoted thereto, an arm on said tray, and a guide rail with

which said arm coöperates to rock the tray about its pivotal connection with the powder charge cage.

In testimony whereof we affix our signatures in presence of two witnesses.
